BY Thomas J. Wallach

ATTORNEY

UNITED STATES PATENT OFFICE

128,939

DESIGN FOR A COMBINED EYEBROW PENCIL AND BRUSH

Florence N. Lewis, New York, N. Y.

Application May 23, 1941, Serial No. 101,112

Term of patent 14 years

To all whom it may concern:

Be it known that I, Florence N. Lewis, a citizen of the United States of America, residing in New York city, county of New York, and State of New York, have invented a new, original, and ornamental Design for a Combined Eyebrow Pencil and Brush, of which the following is a specification, reference being had to the accompanying drawing, forming part thereof, wherein,

Figure 1 is an elevational view of a combined eyebrow pencil and brush showing my new design, and

I claim:

The ornamental design for a combined eyebrow pencil and brush, substantially as shown.

FLORENCE N. LEWIS.
